United States Patent Office.

EDWIN H. GIBBS, OF NEW YORK, N. Y.

Letters Patent No. 97,902, dated December 14, 1869.

FIRE-PLACE.

The Schedule referred to in these Letters Patent and making part of the same

I, EDWIN H. GIBBS, of New York city, have invented an improved "Fire-Place Heater and Range;" and do hereby describe the same.

Nature and Objects of the Invention.

My invention consists,

First, in a novel construction and arrangement of hollow fire-back and basket-grate for heating air for warming apartments.

Second, in combining a water-heating coil with a hollow fire-back, as hereinafter described.

Third, in an oven of new and improved construction to be used with an open fire-place.

General Description.

In the accompanying drawings—

Figure 1 is a vertical section of the apparatus complete.

Figure 2 is a rear view of the same, with the rear plate removed.

Figure 3 represents a horizontal section at $x x$, figs. 1 and 2.

Similar letters of reference indicate corresponding parts in all the views.

A A' represent a basket-grate, the vertical and horizontal bars of which may be made hollow, as shown in figs. 1 and 3.

The back B B' is hollow, forming an air-chamber extending the entire width of the grate, and from the bottom thereof up to the crown.

This air-chamber communicates with the lower ends of the vertical bars A through apertures, $a a$, and with the horizontal bar A' through apertures, $a' a'$, and has also an opening, b , at bottom, to admit cold air to be heated, and one or more pipes, C C, at top, to conduct the heated air to other apartments, or discharge it into the same apartment in which the grate is situated, if required.

D is a water-reservoir, either the upper or the lower pipe d or d' of which may be in permanent communication with a water-supply, and the hot-water may be drawn out by a faucet in the reservoir itself, or at the lower end of the coil d' , which passes around in close proximity or contact with the fire-back B within the hot-air-chamber. The reservoir may rest on the mantel, or wherever convenient.

Resting on the top bar A', of the grate is an oven,

E, the back portion of which extends within the cavity of the fire-back, as shown in fig. 1, and by dotted line in fig. 3, but leaving sufficient space at the back and sides for the passage of the products of combustion to the chimney.

The oven thus placed, will greatly improve the draught of the fire-place, and will utilize the heat thereof in a very advantageous manner for a variety of cooking purposes, either baking, boiling, broiling, or frying; holes for pots, pans, kettles, or griddles, if desired, being formed in the bottom of the oven, as in the top of a stove.

The door E' of the oven exposes the entire front thereof when opened or removed, and whether the door be open or closed, all the smoke and fumes from the cooking will be carried up the chimney through an aperture, e . For baking, this aperture may be covered by a slide.

By extending the hot-air chamber in the fire-back around the sides, bottom, and top, as shown in figs. 2 and 3, the entire surface of the back is utilized for heating, and also protected from injury.

I am enabled to conveniently form said chamber thus, by casting the back of iron. Superior radiation results from the use of iron, while the cost of the back is lessened thereby.

Claims.

The following is claimed as new—

1. The fire-back B B', made of iron, and having a hot-air chamber therein extending on the sides of, over, and beneath the grate, as represented and described, for the purposes set forth.

2. The combination of the hollow grate A A' and hollow fire-back B B', as constructed and arranged substantially as set forth.

3. The combination of the water-coil d' , and hollow fire-back B B', as and for the purposes specified.

4. The oven E, constructed as represented and described, so as to rest on the basket-grate B, as set forth.

5. The aperture e , for conducting fumes and smoke from the interior of the oven to the chimney.

EDWIN H. GIBBS.
